DISPLAY SUPPORT FOR PARALLELEPIPED PACKAGES

Amilcare Dogliotti, Neive, Italy, assignor to
P. Ferrero & C. S.p.A., Alba, Italy

Filed Apr. 22, 1974, Ser. No. 463,023

Claims priority, application Italy Nov. 5, 1973

Term of patent 14 years

Int. Cl. D6—99; D20—02

U.S. Cl. D6—85

FIG. 1

FIG. 2

FIG. 3

FIG. 4

FIG. 5

FIG. 1 is a perspective view of a display support for parallelepiped packages showing my design;

FIG. 2 is a top plan view;

FIG. 3 is a bottom plan view;

FIG. 4 is a left side elevational view, the right side being identical; and

FIG. 5 is a front elevational view thereof.

I claim:

The ornamental design for a display support for parallelepiped packages, as shown and described.
